KATHERINE K. BAKELAAR, OF PASSAIC, NEW JERSEY.

REFILLABLE POWDER-PUFF.

1,171,302.

Specification of Letters Patent. Patented Feb. 8, 1916.

Application filed June 9, 1915. Serial No. 33,070.

To all whom it may concern:

Be it known that I, KATHERINE K. BAKELAAR, a citizen of the United States, and a resident of Passaic, in the county of Passaic and State of New Jersey, have invented a new and Improved Refillable Powder-Puff, of which the following is a full, clear, and exact description.

The object of the invention is to provide a new and improved refillable powder puff, arranged to permit the user to fill the puff with any kind of face powder of the user's choosing, to prevent the powder from coming out too freely, and to allow the user to readily apply any desired amount of powder to the face and to rub it over the desired space on the face.

In order to accomplish the desired result, use is made of a casing having a filling mouth and formed of two sides united along their edges except at the said mouth, one of the sides having perforations, closing means for normally holding the said mouth in closed position, and a perforate distributor overlying the inner face of the said perforate side to distribute the powder in the casing to the said perforations and to retard the passage of the powder to the outer face of the said perforate member. Use is also made of separable fastening devices for fastening the sides together at the mouth and a special closing flap arranged within the mouth to prevent the powder from seeping out of the mouth.

A practical embodiment of the invention is represented in the accompanying drawings forming a part of this specification, in which similar characters of reference indicate corresponding parts in all the views.

Figure 1 is a face view of the powder puff; Fig. 2 is an enlarged sectional side elevation of the same; Fig. 3 is a perspective view of the powder puff with the mouth and closing flap in open position; Fig. 4 is a sectional elevation of the same; and Fig. 5 is a cross section of the same with the mouth and closing flap in open position for filling the puff with powder.

The powder puff is in the form of a casing, preferably made circular in shape, and formed of two sides A and B of powder puff material such as cotton plush, chamois cloth or the like. The pile of the sides A and B extends on the outer faces thereof and the edges of the sides A and B are fastened together, preferably by stitches C, ex-

cept for a short distance to provide a filling mouth D for filling the interior of the casing with powder E of the user's own choosing. The side A is provided in its body 60 portion with perforations or apertures A' formed by punching or stamping out corresponding portions of the body of the fabric, the openings, however, being normally covered by the pile on the outer face of the 65 side A. By this arrangement the powder E within the casing is not liable to flow out of the openings A' unless the puff with its perforate face is lightly struck against the side of the face or other part to be powdered. It is understood that when the powder puff is used in this manner some of the powder passes through the openings A' and into the pile of the side A and some of the powder also passes out from between the 75 pile onto the part of the face touched at the time. The side A can now be used for rubbing the powder in place, but preferably the other side B is used for this purpose so as to prevent too much powder from being 80 applied to the face.

In order to still more restrict the outflow of the powder E through the openings A', use is made of a piece of tarlatan or other netting F overlying the inner face of the 85 side A and secured on its edge to the edge of the side A, preferably by the same stitches C used for fastening the sides A and B together. It will be noticed that this piece of fabric F acts as a distributor to distribute 90 the powder to the openings A' and at the same time to prevent the powder from flowing too freely out of the openings A'. The mouth D is adapted to be closed by separable fastening devices G in the form of a 95 stud G and a socket G' secured to short pieces of linings H and I, of closely woven fabric, of which the piece H is doubled and secured along one edge to the side A along the mouth thereof and the piece I is secured 100 along one edge to the side B of the casing at the mouth thereof. When the sides are pressed together at the mouth the stud G engages the socket G' to close the mouth and hold the same closed.

In order to prevent the powder from accidentally passing out through the mouth at opposite sides of the fastening members G, G', use is made of a closing flap I' formed by folding the opposite or free edge of the 110 lining I. On the outer face of the closing flap I' are secured sockets J adapted to be

engaged by studs J' formed on the outer face of the lining H, the sockets and studs J, J' being locked on opposite sides of the socket G' and the stud G. Thus when the 5 flap I' is fastened to the lining H the mouth opening is covered, and when the fastening members G, G' are engaged with each other then the mouth is closed and held against opening. When it is desired to fill the puff 10 with powder the stud G and socket G' are first disconnected and then the sockets and studs J, J' are disengaged from each other to allow of completely opening the mouth to fill the casing with powder. After this 15 has been done the sockets and studs are re-engaged with each other to hold the casing closed at the mouth.

The powder puff shown and described is 20 very simple in construction and allows convenient filling of the puff with any kind of face powder of the user's choice, and the powder can be readily passed out of the casing in small quantities to the pile of the side A and to the face of the user, so that by the 25 use of the side B the powder can be readily rubbed over the portion of the face to be powdered. As the pile overlies the openings A' in a loose fashion, it is evident that the powder is retained within the casing 30 while carrying the puff about and the powder is also restrained from passing out of the openings by the netting F.

Having thus described my invention, I 35 claim as new and desire to secure by Letters Patent:

1. A refillable powder puff, comprising a flat casing of puff material having a filling mouth along its edge for filling the casing with powder, one side of the said casing 40 having a plurality of apertures formed therein for the passage of the powder from the interior of the casing to the face of the said apertured side, and separable fastening devices for fastening the sides of the casing 45 together at the mouth.

2. A refillable powder puff, comprising a casing having a filling mouth, and formed of two sides of puff material united along the edges except at the mouth, one of the 50 sides having a plurality of apertures formed therein, a fabric closure within the mouth of the casing, and having members secured to opposite sides of the casing, separable fastening devices for securing the members 55 of the closure together, and a distributor of loosely woven fabric overlying the inner face of the apertured side of the casing to distribute the powder in the casing to the said perforations and to retard the passage 60 of the powder to the outer face of the said apertured side.

3. A refillable powder puff, comprising a flat casing having a filling mouth and formed of two sides united along their edges 65 except at the said mouth, the said sides be-

ing formed of pile fabric material with the piles at the outer faces, the body of one of the sides being formed with a plurality of perforations covered by the surrounding pile, a piece of netting overlying the inner 70 face of the perforate side of the casing and secured at its edge to the edge of said side, and closing means for normally holding the said mouth in closed position and including separable fastening devices. 75

4. A refillable powder puff, comprising a flat casing having a filling mouth along its edge for filling the casing with powder, the casing being formed of two sides formed of pieces of pile fabric united along their edges 80 except at the said mouth, the pile of the pieces being on the outer faces of the sides, one of the sides having perforations, separable fastening members on the inner faces of the sides at the mouth for closing the latter, and a fabric closure within the said 85 mouth and formed of two pieces of closely woven fabric, one of which is doubled and attached along one edge to the inside of the said casing at its mouth, the other piece of 90 fabric (being not doubled) and attached along one edge to the inside of the opposite side of said casing at its mouth, the opposite edge of said piece of fabric being folded to form a closing flap and carrying means for 95 releasably engaging a fastening means attached to the said doubled piece of fabric at a point adapted to bring it into engagement therewith.

5. A refillable powder puff, comprising a flat casing having a filling mouth along its edge for filling the casing with powder, the casing being formed of two sides formed of pieces of pile fabric mounted along their edges except at the said mouth, the pile of 100 the pieces being on the outer faces of the sides, one of the sides having perforations, separable fastening members on the inner faces of the sides at the mouth for closing the latter, a fabric closure within the said 105 mouth and formed of two pieces of closely woven fabric, one of which is doubled and attached along one edge to the inside of the opposite side of said casing at its mouth, the opposite edge of said piece of fabric being folded to form a closing flap and carrying means for 110 releasably engaging a fastening means attached to the said doubled piece of fabric at a point adapted to bring it into engagement therewith, and a piece of netting overlying the inner face of the said perforate side of 115 the casing, the edge of the said netting being secured to the edge of the perforate side. 120

6. A refillable powder puff, comprising a casing formed of two sides of puff material, and having a filling mouth along its edge for filling the casing with powder, one side of 130

the said casing having perforations for the passage of the powder from the interior of the casing to the face of the said perforate side, a closure formed of two pieces of fabric material, one of which is doubled and attached along one edge to the inside of the said casing at its mouth, the other piece of fabric being attached along one edge to the inside of the opposite side of said casing at its mouth, the opposite edge of said piece of fabric being folded to form a closing flap, fastening devices secured to the said fabric pieces at the center of the mouth for closing

the same, and fastening devices for securing the face of the closing flap to the face of the 15 doubled piece of fabric, the said fastening devices being located at opposite sides of the first mentioned fastening devices.

In testimony whereof I have signed my name to this specification in the presence of 20 two subscribing witnesses.
